UNITED STATES PATENT OFFICE

2,049,354

THERMAL RELAY

Charles H. Chapman, Scotia, N. Y., assignor to
General Electric Company, a corporation of
New York

Application January 19, 1935, Serial No. 2,514

7 Claims. (Cl. 200—116)

My invention relates to electric switches or relays, more particularly to thermal relays and has for an object the provision of a thermal relay which is simple and inexpensive to construct and reliable in its operation.

In Patent 1,854,007, issued April 12, 1932, to L. J. Weber there is disclosed a thermal relay which comprises a bimetallic element and a movable member normally biased into an abutting engagement with the free end of the bimetallic element. Heating means are provided therefore and when the bimetallic element flexes sufficiently so that the free end thereof moves out of abutting relationship with the movable member the movable member is actuated by its biasing means to operate a movable control bar operatively associated with suitable circuit controlling contacts.

While relays of the type disclosed in the Weber patent are simple and inexpensive, some difficulty has been encountered in the operation thereof due partially to the relatively strong biasing force which is necessary to operate the movable member to move the control bar, and the fact that this biasing force on the movable member, which engages the end of the bimetallic element, imposes a relatively great load on the bimetallic element. The amount of work which the element must accomplish in moving to releasing position is accordingly rather large and it is desirable in a relay of this type that the load on the bimetallic element shall be relatively small, so as to provide for low watt input and accurate adjustment of the relay, and that the biasing force on the movable member shall be relatively great in order positively to operate the control bar. Accordingly, it is a further object of my invention to provide a thermal relay of this type in which the load on the thermal element is substantially unaffected by the biasing force on the movable member.

In carrying out my invention in one form I provide a thermal relay comprising a bimetallic element having a free end, a pivoted latch member lightly biased into engagement with the free end of the bimetallic element and a movable member strongly biased to operate a movable control bar when released by the latch. The latch member and the movable member are provided with interengaging latching portions, the paths of movement of which are so related that the force exerted on the bimetallic element by the latch is substantially independent of the biasing force on the movable member, and the two members are disposed adjacent the control

bar in overlapping relation so that when the control bar is returned to its normal position by suitable resetting means, the latch member and the movable member will be engaged thereby and respectively returned to their normal latching positions.

For a more complete understanding of my invention, reference should now be had to the drawing in which Fig. 1 is a front view of a three-phase motor starting switch provided with a pair of thermal relays embodying my invention; Fig. 2 is a side view of the switch; Fig. 3 is a slightly enlarged perspective view of my improved thermal relay with the heater removed and Figs. 4 to 6 inclusive are enlarged fragmentary sectional views illustrating the operation of the device shown in Fig. 3.

Referring to the drawing, the motor starting switch shown in Figs. 1 and 2 comprises essentially a three pole switch 10, rotatively mounted 20 in the bearings 11 on a base 12 and mechanically connected to be operated by an electromagnet 13. Each of the thermal relays 14 embodying my invention is connected to a corresponding one of the circuits controlled by the motor starting 25 switch and is arranged to operate an actuating member or control bar 15 carrying the control contact 16 which is connected in the energizing circuit of the electromagnet 13. The thermal relays are suitably connected in the circuit of the 30 motor starting switch, preferably as shown in the above-referred to Weber patent.

As shown in Fig. 3, each of the thermal relays 14 comprises a unitary structure, the terminal working parts of which are carried by a channel 35 frame member 17 of substantially inverted L shape, one end of which is provided with an upturned lug 18 for mounting the frame on a support 19 extending from the base 12. Secured to the frame 17 is a supporting spring bracket 20 to 40 which a bimetallic element 21 is fixedly secured, as by spot welding. In order to provide for factory adjustment of the bimetallic element 21, the end of the supporting bracket 20 remote from the bimetallic element is spot welded to the frame 17 45 and an adjustable screw 22 threadedly engages another portion of the support 20 with the end of the screw bearing against the frame 17. It will be apparent that as the screw 22 is adjusted, the supporting bracket 20 is moved toward or away from the frame 17 to adjust the position of the free end of the bimetallic element 21. When the bimetallic element has been so adjusted 50 to the proper initial position, the supporting 55

bracket 20 may be permanently secured to the screw 22 as by placing a drop of solder thereon.

The other end of the frame 17 is provided with a pair of supporting ears 23 between which extend a pair of bearing pins 24 and 25. Pivots mounted on the pin 24 is a movable member 26 a portion of which is disposed adjacent the control bar 15. A spring 27 surrounding the pin 24 engages the frame 17 and the movable member 26 so as to bias the member 26 about its pivot in a clockwise direction as viewed in Fig. 4 to operate the control bar 15. Pivots mounted on the pin 25 is a latch 28 provided with a slot 29 extending substantially the length thereof, the unslotted end portions of the latch 28 forming latchable and latching portions 30 and 31 respectively. A spring 32 surrounding the pin 25 serves to bias the latchable portion 30 into abutting engagement with the free end 21' of the bimetallic element 21, whereby the latch 28 is held in the latching position shown in Figs. 3 and 4. It will be observed that the paths of movement of the latch member and the movable member 26 partially overlap and that a portion of the movable member 26 extends into the slot 29, an extending finger 33 formed thereon being normally engaged by the latching portion 31 of the latch 28 in latching relation as shown in Fig. 4.

It will be remembered that it is desirable in relays of this type that the load on the bimetallic element shall be relatively small and that the biasing force on the movable member shall be relatively great, and accordingly the biasing springs 27 and 32 are respectively arranged to exert a relatively heavy and a relatively light biasing force on the movable member 26 and on the latch 28 respectively, the paths of movement of the engaging portions 31 and 33 being so arranged that the load imposed on the free end 21' of the bimetallic element by the latch 28 is substantially unaffected by the biasing force on the movable member 26. As may be seen by reference to Figs. 4, 5 and 6, the engaging portion 33 carried by the movable member 26 tends to move substantially vertically as the member 26 rotates about the pin 24 in a clockwise direction and the latching portion 31 on the latch 28 tends to move substantially horizontally to the right, as viewed in the drawing, under the bias exerted by the spring 32. Because of this right angle relation of the paths of movement of the engaging portions 31 and 33 it will be seen that the engaging portion 33 exerts substantially no horizontal force on the latching portion 31 tending to rotate the latch 28 about its pivot and accordingly the load imposed on the bimetallic element 21 by the latch 28 is substantially unaffected by the biasing force of the spring 27. To express the engaging relation of the portions 31 and 33 a little differently, it will be observed that the portion 31 on the latch 28 is arranged substantially radially with respect to the pivot pin 25 so that the line of action of the force exerted on the portion 31 passes through the pivot pin 25 and exerts substantially no rotative moment on the latch 28.

Referring again to Figs. 1 and 2, the frame 17 is secured to the support 19 by a screw 34 which also serves to secure thereto one terminal of a heater 35, the other terminal of which is secured by a screw 36 to a support 37 extending from the base 12, the supports 37 and 19 serving as conducting leads for the heater 35. The heater 35, which has the form of a flattened helix, surrounds a substantial portion of the bimetallic

element 21 and is preferably of the removable type disclosed in the above-referred to Weber patent. In order that the latch 28 shall be free to move past the heater when the bimetallic element flexes to release the latch, the free end 21' of the bimetallic element is angularly offset toward the latch as shown.

As shown, the bimetallic element 21 and the latch 28 are arranged with the latch substantially perpendicular to the main portion of the bimetallic element 21 and it will be apparent that when the element 21 is heated, the free end 21' of the bimetallic element due to its offset relation to the main portion moves in an arc about the fixed end of the bimetallic element with respect to which arc the latch 28 is in non-tangential relation. Accordingly, in order for the free end of the bimetallic element to move out of abutting engagement with the latch the bimetallic element must, unless provision is made to prevent it, force the latch 28 backwards against the biasing force on the latch. While the additional load thus imposed upon the bimetallic element is not excessive with my improved lightly biased latching arrangement, I have found that the efficiency of operation of the thermal relay may be considerably improved by forming the latchable portion 30 of the latch 28 at an angle with the main portion, as shown, so as to provide an engaging surface which is substantially tangential to the arc of movement of the free end of the bimetallic element.

In Figs. 1 and 2, I have shown the motor starting switch in its open position and my improved thermal relays in their normal positions with the control contact 16 in closed circuit position in the energizing circuit of the electromagnet 13. With the starting switch closed by energization of the electromagnet 13 by means of a suitable switch (not shown) to supply current to a load device, upon the occurrence of abnormal current conditions, one or more of the heaters 35, which are connected in series circuit relation with the associated contacts of the switch 18, will cause the free end of the associated bimetallic element to move outwardly from the position shown in Fig. 4 to the releasing position shown in Fig. 5 whereupon the latch member 28 will be rotated by the spring 32 to move the latching portion 31 horizontally to the right, thereby releasing the movable member 26 for rotation about its pivot in a clockwise direction to the tripping position shown in Fig. 5 and the control bar 15 will be operated thereby to move the control contact 16 to open circuit position.

In order to reset the control contact 16 to the closed circuit position after the bimetallic element 21 has cooled, a reset button 38 is provided which may be operated to engage an arm 39 extending from the control bar 15 and thereby operate the control contact 16 in a counter-clockwise direction about its pivot 40. Due to the yielding mounting of the contact 16, the control bar 15 may be moved past its normal position to the extreme position shown in Fig. 6, and it will be seen that the control bar 15 engages the latch 28 to move the latch beyond the free end 21' of the bimetallic element and engages the member 26 to operate it to the extreme position there shown. When the reset button 38 is released the movable member 26 and the latch 28 will be returned to their respective normal position shown in Fig. 4 by the biasing springs 27 and 32, the latchable portion 30 engaging the free end 21' of the bimetallic element and the portions 75

31 and 33 engaging each other to prevent further clockwise movement of the member 26.

While I have shown a particular embodiment of my invention, it will be understood, of course, 5 that I do not wish to be limited thereto since many modifications may be made, and I, therefore, contemplate by the appended claims to cover any such modifications as fall within the true spirit and scope of my invention.

10 What I claim as new and desire to secure by Letters Patent of the United States, is:

15 1. A thermal device comprising a movable member biased from one position to a second position, means including a latch having a latching portion disposed in the path of said movable member for latching said member in said one position, said latch also having a latchable portion, a thermal element having a movable portion disposed in the path of said latchable portion and means for biasing said latch into abutting engagement with said movable portion of said thermal element and for moving said latch to release said movable member when said thermal element moves out of the path of said latch, the respective 20 engaging portions of said latch and said movable member being movable substantially at right angles to each other, whereby the force exerted on said thermal element by said latch is substantially independent of the force exerted on said latch by said movable member.

25 2. A thermal device comprising a movable member biased from one position to a second position, a pivoted latch comprising latching and latchable portions extending outwardly from the pivot point thereof, said latching portion being disposed in the path of said movable member for latching said member in said one position, a movable bimetallic element normally disposed in the path of said latchable portion of said latch, and 30 means for biasing said latch about said pivot point against said bimetallic element and for rotating said latch to release said movable member when said bimetallic element moves out of the path of said latchable portion, said movable member being arranged to exert a substantially radial force on said latching portion of said latch whereby the force exerted on said bimetallic element by said latch is substantially independent 35 of the bias on said movable member.

30 3. A thermal relay comprising a movable member normally biased from one position to a second position, means including a pivoted latch normally engaging said movable member for holding said movable member in said one position, said latch being biased for rotative movement about its pivot to unlatching position, and a bimetallic element having a movable portion abuttingly engaging said latch for normally holding said latch in latching position against the bias thereon, the engaging portions of said latch and said movable member being so arranged relative to the pivot point of said latch that the biasing force on said movable member exerts substantially no rotative moment on said latch, whereby the pressure between said abuttingly engaged portions of said latch and said bimetallic element is substantially unaffected by the bias on said movable member.

4. A unitary thermal device comprising an L shaped frame, a movable member pivoted on one leg of said frame and biased from one position to a second position, a latch pivoted on said one leg and having a latching portion disposed in the path of said movable member for latching said member in said one position, said latch including

a latchable portion, a bimetallic element having one end fixed to the other leg of said frame and having a free end disposed in the path of said latchable portion, and means for biasing said latch against said free end of said bimetallic element and for moving said latch about its pivot to release said movable member when said bimetallic element moves out of the path of said latch, the respective engaging portions of said movable member and said latch being arranged 10 to move substantially at right angles to each other, whereby the force exerted on said bimetallic element by said latch is substantially independent of the force exerted on said latch by said movable member.

15 5. In combination with a control device having a control bar movable from one position to a second position and resetting means for returning said control bar to said one position, a thermal device comprising an L shaped frame, a movable member pivoted on one leg of said frame and biased to operate said control bar to said second position, means including a latch pivoted on said one leg and having a latching portion engageable with said movable member for latching said member against movement to its biased position, said latching portion being movable substantially at right angles to the path of movement of said movable member whereby the bias on said movable member exerts substantially a 20 radial force on said latch, said latch also having a latchable portion, means for biasing said latch from latching to releasing position, a bimetallic element extending from the other leg of said frame and having a free end normally abuttingly 25 engageable with said latchable portion in latching position, said bimetallic element being movable out of the path of said latchable portion to release said latch, said latchable portion extending adjacent said movable member in engageable relation with and biased toward said control bar whereby said latch and said movable member are resettable by the return movement of said control bar to said one position.

30 6. In combination with an electric switch having a control bar movable from one position to a second position and resetting means for returning said control bar to said one position, a thermal device comprising a movable member adjacent said control bar, means for biasing said 35 movable member to operate said control bar to said second position, means including a latch pivoted adjacent said movable member having a latching portion engageable with said movable member for latching said movable member against movement by said biasing means, said latching portion extending substantially radially from the pivot of said latch and being movable substantially at right angles to the path of movement of said movable member whereby said bias 40 on said movable member exerts substantially no rotational moment on said latch, said latch also having a latchable portion, means for biasing said latch from latching to releasing position, and means including a bimetallic element having a movable portion normally abuttingly 45 engageable with said latchable portion for retaining said latch in latching position against its bias and movable out of the path thereof to release said latch, said latchable portion extending adjacent 50 said movable member in engageable relation with and biased toward said control bar whereby said latch and said movable member are resettable by the return movement of said control bar to said one position.

7. A thermal device comprising a bimetallic element having a fixed end and a free end, a heater adjacent an intermediate portion of said element, said free end of said element being adapted to move in an arc about said fixed end when said element is heated, and a movable member normally biased into abutting engagement with said free end of said bimetallic element, said movable member engaging said element non-

tangentially to said arc of movement whereby said member is free to move past said heater when released by said bimetallic element, the portion of said movable member over which said free end of said bimetallic element moves to releasing position being formed at an angle to provide an engaging surface tangential to said arc of movement.

CHARLES H. CHAPMAN.
